(57) **CLAIM**

The ornamental design for a powder particle feeder for weighing as shown and described.

DESCRIPTION

FIG. 1 is a perspective view of a powder particle feeder for weighing showing the claimed design;

FIG. 2 is a front view thereof;

FIG. 3 is a rear view thereof;

FIG. 4 is a left side view thereof;

FIG. 5 is a right side view thereof;

FIG. 6 is a plan view thereof;

FIG. 7 is a bottom view thereof;

FIG. 8 is a perspective view thereof with doors shown in an open position;

FIG. 9 is a front view of the powder particle feeder for weighing in a usage state; and,

FIG. 10 is a perspective view thereof in the usage state. The broken lines in the figures show portions of the powder particle feeder for weighing that form no part of the claimed design.

1 Claim, 10 Drawing Sheets
